(57) **CLAIM**

The ornamental design for a phone hanging device, as shown and described.

DESCRIPTION

FIG. 1 is a front view of a phone hanging device;

FIG. 2 is a back view thereof;

FIG. 3 is a right-side view thereof;

FIG. 4 is a left-side view thereof;

FIG. 5 is a top view thereof;

FIG. 6 is a bottom view thereof; and,

FIG. 7 is a perspective view of the phone hanging device of FIG. 1 shown in an environment of use.

The dash-dot-dash broken lines represent boundaries and form no part of the claimed design. The dash-dot broken lines between the solid lines of the phone hanging device depict portions of the article that form no part of the claimed design. The dash-dot broken lines in FIGS. 1-7 showing a phone and phone case and the broken lines in FIG. 8 showing the interior of a car illustrate an environment of use and form no part of the claimed design.
